UNITED STATES PATENT OFFICE.

CHARLES E. EGAN AND GEORGE P. MATTHEWS, OF CHARLESTON, WEST VIRGINIA,
ASSIGNORS OF ONE-SIXTH TO EDWARD CALDERWOOD AND FIVE-SIXTHS TO WADE
H. GUTHRIE, OF CHARLESTON, WEST VIRGINIA.

MIXING DEVICE.

1,186,386.

Specification of Letters Patent.

Patented June 6, 1916.

Application filed October 26, 1915. Serial No. 58,018.

To all whom it may concern:

Be it known that we, CHARLES E. EGAN and GEORGE P. MATTHEWS, citizens of the United States, residing at Charleston, in the county of Kanawha and State of West Virginia, have invented certain new and useful Improvements in Mixing Devices; and we do declare the following to be a full, clear, and exact description of the invention, such 10 as will enable others skilled in the art to which it appertains to make and use the same.

Our invention relates broadly to improvements in mixing devices and more particularly to a device adapted to be disposed within the fuel outlet tube of an ordinary carburetor, so constructed as to effectively mix the fuel and air passing through such tube to compound the same into a highly volatile mixture.

The object of the invention is to provide a device of the class specified which may be simply and easily manufactured and marketed, and which when applied to use will be highly efficient and durable and will have no wearing parts whatever.

With this general object in view, the invention resides in certain novel features of construction and in unique combinations of parts to be hereinafter fully described and claimed, the descriptive matter being supplemented by the accompanying drawing which constitutes a part of this application and in which:

Figure 1 is a vertical sectional view of a portion of the fuel outlet of a carburetor showing the application of the invention thereto, the latter being shown in elevation; Fig. 2 is a similar view disclosing a vertical section of the improved device; Fig. 3 is a horizontal sectional view taken substantially on the plane indicated by the line 3—3 of Fig. 1; Fig. 4 is a plan view of one of the fuel deflecting members, and Fig. 5 is a detail horizontal section as seen on the plane designated by the line 5—5 of Fig. 2.

In specifically describing the invention shown in the drawing above briefly described, reference will be made to such drawing by similar characters placed on corresponding parts throughout the several views. To this end, T represents the fuel outlet tube of a mixing device, such tube being shown as provided with an outstanding annular flange F at its lower end secured

by bolts or the like B to a similar flange F¹ projecting outwardly from the discharge nipple N of the carburetor, an appropriate gasket G of rubber or other suitable material being disposed between the two flanges. 60 Having a trio of equally spaced arms 1 radiating from its center, is a spider 2, the ends of said arms being embedded in the gasket G in contact with the flange F and preferably having depending stops 3 abutting the inner side of the nipple N, whereby the spider is held against lateral shifting. Rising from the center of the spider 2 and secured thereto in any preferred manner, is an upright rectangular shaft 4 having a 70 reduced upper end 5 upon which a clamping nut 6 is threaded.

Mounted non-rotatably on the shaft 4 and having rectangular openings 7 at their centers receiving said shaft, are a number of 75 vertically spaced fuel deflecting members 8, all of which are of circular formation, being preferably constructed of sheet metal, and of a size to totally fill the cross sectional area of the tube T. The several 80 members 8 are slit radially at intervals as disclosed more particularly at 9 in Fig. 4, whereby to provide such members with a plurality of radiating blades 10, such blades being formed with perforations 11 passing 85 therethrough at right angles to the opposite faces thereof. The inner ends of the blades 10 are so twisted as to dispose such blades obliquely of the axes of the numerous members as clearly shown in Fig. 1, the 90 blades of the three members being disposed parallel to and opposite each other.

Interposed between the members 8 is a plurality of additional deflecting members 8^a which are identical in construction with 95 said members 8 with the exception that their blades 10^a are inclined in the opposite direction, being disposed at approximately right angles to the blades 10 and having their opposite edges in contact with the intermediate portions of said blades 10. Similarly, the edges of the blades 10 contact with the intermediate portions of the blades 10^a. This arrangement is shown most clearly in Fig. 1, and is particularly 100 advantageous, since it provides a multiplicity of zig-zag passages through which the fuel and air must pass, such passages being in turn divided into a great number of smaller and supplemental passages by the 110

- perforations in the blades 10 and 10^a. Thus it will be evident that the air and fuel drawn through the network formed by the intermeshing blades of the several deflecting members, will be effectively compounded and mixed into an efficient highly volatile mixture which will produce first class results in the cylinder or cylinders of the engine.
10. Although the several members 8 and 8^a could well be spaced from each other by any preferred means at their centers, a number of washers 12 are preferably used for this purpose as shown in Fig. 2, certain of these 15 washers being positioned between the lowermost member and the spider, while another is interposed between the nut 6 and the uppermost member.

Particular emphasis is laid upon the fact 20 that the construction above described fills the entire cross sectional area of the tube T and thus prevents any fuel and air from passing to the engine cylinders without first 25 passing through the numerous zig-zag passageways above described. Also, it is of great 30 advantage that the numerous members be non-rotatably mounted, since by so doing, no wearing parts whatever need be used, thus providing a device which will not deteriorate with age.

From the foregoing description, taken in connection with the accompanying drawing, it will be obvious that although the construction of the device is simple and inexpensive, the article will be highly efficient 35 and durable and will possess a number of advantageous features.

In the drawing, certain specific arrangements of parts have been shown for the attainment of probably the best results, and in the preceding description such arrangements have been described, but obviously, numerous changes in form, proportion, and minor details may be resorted to without departing 45 from the spirit of the invention as claimed.

We claim:

1. The combination with the fuel outlet tube of a carburetor; of a pair of spaced axially aligned non-rotatable fuel deflecting 50 members disposed transversely therein and

filling the cross sectional area thereof, said members having radiating perforated blades disposed obliquely of their axes, the blades of one member being parallel to and positioned opposite those of the other, and 55 an additional deflecting member interposed between said pair of members and having radiating perforated blades extending obliquely of its axis and disposed at an angle to the aforesaid blades and in staggered relation thereto, the edges of the blades of the additional member being positioned in contact with the intermediate portions of the other blades and vice versa.

2. The combination with the fuel outlet tube of a carburetor; of a spider secured therein, a rectangular shaft secured to said spider and positioned at the axis of the tube, a pair of fuel deflecting members disposed transversely in said tube and having 70 rectangular openings at their centers receiving the shaft, said members being of a size to fill the cross sectional area of the tube and having a plurality of radiating perforated blades disposed at an angle to their 75 axes, an additional deflecting member interposed between the other members and likewise having a rectangular opening receiving the shaft, said additional member being also formed with a plurality of radiating 80 perforated blades disposed opposite the spaces between the blades of the other members, the edges of the blades of the additional member being disposed in contact with the intermediate portions of the blades 85 of the other members, and vice versa, a plurality of washers spacing the several members on the shaft, an additional washer spacing said members from the spider, a nut threaded on the free end of the shaft, and 90 another washer interposed between said nut and the adjacent deflecting member.

In testimony whereof we have hereunto set our hands in presence of two subscribing witnesses.

CHARLES E. EGAN.
GEORGE P. MATTHEWS.
